[57] **CLAIM**

The ornamental design for a decorative top adapted to be placed over the existing roof of a truck, as shown and described.

DESCRIPTION

FIG. 1 is a left side elevational view of a decorative top adapted to be placed over the existing roof of a truck showing our new design;

FIG. 2 is an enlarged left side elevational view thereof; FIG. 3 is an enlarged right side elevational view thereof;

FIG. 4 is an enlarged top perspective view thereof;

FIG. 5 is an enlarged front elevational view thereof;

FIG. 6 is an enlarged rear elevational view thereof;

FIG. 7 is a left side elevational view of a second embodiment of a decorative top adapted to be placed over the existing roof of a truck showing our new design;

FIG. 8 is an enlarged left side elevational view of the top shown in FIG. 7;

FIG. 9 is an enlarged right side elevational view of the top shown in FIG. 7;

FIG. 10 is an enlarged front elevational view of the top shown in FIG. 7;

FIG. 11 is an enlarged rear elevational view of the top shown in FIG. 7.

The top view of the second embodiment of the claimed design is substantially the same as that of the first embodiment shown in FIG. 4 of the drawing.

The broken line showing of a truck in FIGS. 1 and 7, is for illustrative purposes only and forms no part of the claimed design.
